FURNITURE CONSTRUCTION

Solly Karsakov and George A. Kramer, Springfield, Mass., assignors to Berkshire Upholstered Furniture Co., Springfield, Mass., a corporation of Massachusetts

Application February 9, 1942, Serial No. 430,032

3 Claims. (Cl. 5—47)

This invention relates to improvements in furniture construction and is directed more particularly to an article of furniture such as a couch or davenport which is converted into a bed.

The principal objects of the invention is the provision of an article of furniture in the form of a convertible couch and bed that is characterized by its simplicity of form so as to be economical to produce and, at the same time, rigid and strong but relatively light in weight and easily and readily converted. The invention may be applied to a chair where the seat and back are relatively shiftable.

The novel features of the invention are adapted for broad application wherever it is desired to convert an article of furniture from one form to another and the novel characteristics are adapted for producing furniture from various materials as well as furniture that may vary in shape, style and dimensions.

In the drawing:

Figs. 1, 2 and 3 are small scale diagrammatic end views showing the principal elements of the structure of the invention in various relative positions;

Fig. 4 is a plan view of the supporting frame of the structure;

Fig. 5 is a front elevational view of the structure of the construction of the invention;

Fig. 6 is an end elevational view of the structure shown in Fig. 5;

Fig. 7 is a transverse sectional elevational view of the structure shown in Figs. 5 and 6; and

Fig. 8 is a partial inverted plan view of the seat part of the furniture structure.

Referring now more in detail to the drawing, the invention will be fully described.

The principal elements of the furniture construction includes a supporting frame 2, a seat section 4 and a back section 6 that are movable relative to one another.

In Fig. 1 the seat section 4 is shown as resting on the frame 2 with the back 6 in back-supporting position. These members 4 and 6 are simultaneously movable from the position shown in Fig. 1 to and through an intermediate position shown in Fig. 2 to a bed forming position shown in Fig. 3.

The frame 2 has end members 8 and front and back members 10 and 12 suitably secured together and there may be longitudinal or transverse elements extending between those shown to provide stiffness and rigidity. All this will be within the skill of one skilled in the art.

The seat section 4 includes end members such as 14 and front and back members 16 and 18 all suitably secured together with such other longitudinal or transverse members as may be desired.

5 The seat section 4 is adapted to rest on the frame in seat-forming position or bed forming position and to be moved relative to the frame between said positions.

The back section 6 has end members 20 and top and bottom longitudinal members 22 and 24 suitably secured together with such other longitudinal or transverse members as may be desired.

10 The seat and back sections are provided with springs, upholstering and covering material not shown and the frame is provided with such padding and covering material as may be desired. The form and construction of the padding, springs, upholstering, covering and the like form no part of the present invention.

15 Means are provided on the seat and back sections for the springs, etc., and may be made to accommodate said springs and upholstering. In the form of the invention shown for such a purpose there are blocks 30 and 32 fixed to the seat

20 section and blocks 34 and 36 are fixed to the back section, the said blocks 30 and 32 being omitted in Figs. 5 and 7 for clearness. Hinge means 38 are secured to the blocks 32 and 34 of the seat and back sections to facilitate relative swinging movements of the sections.

25 Lock members 40 are slidable in the blocks 32 and are arranged so that their rear ends may project beyond the blocks 32 beneath the back section as shown in Fig. 6. As shown with the seat section resting on the frame the back is held in the back supporting position shown.

30 A longitudinal member 42 is secured to the locks and a manually engageable handle member 44 is carried thereby that extends through a slot 46 of a transverse member 48 of the seat section, see Fig. 8. By grasping the handle member 44 the member 42 is moved outwardly to withdraw the locks from engagement with the back section.

35 Forward and inner or front and back guides 50 and 52 are carried at each end of the seat section on the lower side thereof and are spaced apart to receive therebetween the front member 10 of the frame when the seat section is in position shown in Fig. 7. The outer or forward end of guides 50 abut the rear side of frame member 10 when the seat is in the position shown in Fig. 6. Also in this position the end of members 52 abut stops 56 associated with frame 2. The guides 50 and 52 are in substantially the same plane and are adapted to slide against the inner

sides of the end member 8 of the frame when the seat section moves on the frame.

Stop means which may be in the form of flexible strap 69' have opposite ends secured to the frame 2 and to the back section 6. This limits movement of the seat section 4 from the position shown in Fig. 6 to that shown in Fig. 7 and facilitates movement of the section from the position shown in Fig. 2 to that of Fig. 3.

A manually engageable handle member 60 is slideable in a bracket 62 secured to the forward under side of the seat section and a recess is provided in the front face of frame member 10. In moving the sections from couch-forming position shown in Fig. 1 the member 60 is grasped and the sections simultaneously swung clockwise and moved forwardly to an intermediate position approximately as shown in Fig. 2.

The members 60' limit the forward movement of the sections relative to the frame and when in intermediate position the member 42 of the seat section is moved upwardly by manipulation of member 44 so as to withdraw locks 40 upwardly from engagement with the seat section. Then the seat section is lowered by swinging counterclockwise so that the front member 10 of the frame is received between guides 50 and 52 of the seat as shown in Fig. 7 where the seat and back are in substantial parallel bed forming position shown in Fig. 3.

To move the sections from bed forming position the seat section is swung upwardly clockwise when the locks drop between the seat and back sections to the position of Fig. 6. Then the seat is swung counterclockwise and simultaneously moved rearwardly of the frame to a horizontal rest position at the rear thereof whereupon the guides 52 abut stops 56 and the forward ends of guides 50 abut the inner face of frame member 10.

The invention may be embodied in other specific forms without departing from the essential characteristics thereof. Hence, the present embodiments are therefore to be considered in all respects merely as being illustrative and not as being restrictive, the scope of the invention being indicated by the appended claims rather than by the foregoing description, and all modifications and variations as fall within the meaning and purview and range of equivalency of the appended claims are therefore intended to be embraced therein.

What it is desired to claim and secure by Letters Patent of the United States is:

1. Furniture construction comprising in combination, a frame, a seat section and a back section slideable on said frame, hinged connections between adjacent sides of said sections whereby said sections are movable simultaneously on said

frame between bed and seat forming positions and are relatively swingable between bed and seat forming relations, releasable manually operable locking means slideable in the seat section engageable with the back section to hold the latter in seat forming relation relative to the former in either bed or seat forming positions of the sections, and stop means carried by the seat section engageable with said frame to releasably hold said sections against movement in seat and bed forming relation, said locking means including a member slideable in the seat section for positioning beneath and supporting the back section when the said sections are in seat forming position.

15. 2. Furniture construction comprising in combination, a frame, a seat section and a back section slideable on said frame, hinged connections between adjacent sides of said seat and back sections whereby said sections are movable simultaneously on said frame between bed and seat forming positions and are relatively swingable between bed and seat forming relations, releasable manually operable locking means slideable in the seat section engageable with the back section to hold the latter in seat forming relation relative to the former in either bed or seat forming positions of the sections, and stop means carried by the seat section engaging said frame to releasably hold said sections against movement in seat and bed forming position, said locking means including members slideable in the seat section at opposite ends thereof for positioning beneath and supporting opposite ends of the back section when said sections are in seat forming position and connections between said members to facilitate simultaneous operation thereof.

35. 3. Furniture construction comprising in combination, a frame, a seat section and a back section slideable on said frame, hinged connections between adjacent sides of said sections whereby said sections are movable simultaneously on said frame between bed and seat forming positions and are relatively swingable between bed and seat forming relations, releasable manually operable locking means slideable in the seat section engageable with the back section to hold the latter in seat forming relation relative to the former, and stop means carried by the seat section engaging said frame to releasably hold said sections against movement in seat and bed forming position, said stop means including separate blocks associated with said seat section spaced apart to engage a part of said frame therebetween when the sections are in bed forming position and arranged to abut spaced parts of the frame when the sections are in seat forming position.
